DESIGN FOR A COMBINED BED LAMP, CLOCK, AND SUPPORT THEREFOR

Milton N. Tigerman and Alexander R. Tigerman,
Chicago, Ill.

Application December 12, 1940, Serial No. 97,272

Term of patent 7 years

To all whom it may concern:

Be it known that we, Milton N. Tigerman and Alexander R. Tigerman, both citizens of the United States residing at Chicago, Cook County, Illinois, have invented a new, original, and ornamental Design for a Combined Bed Lamp, Clock, and Support Therefor, of which the following is a specification, reference being had to the accompanying drawing, forming part thereof.

Figure 1 is a perspective view of a combined bed lamp, clock, and support therefor, showing our new design; and

Figure 2 is an end view of the combined bed lamp, clock, and support therefor.

The dominant features of our design reside in the portions shown in full lines.

We claim:

The ornamental design for a combined bed lamp, clock, and support therefor, as shown and described.

MILTON N. TIGERMAN.
ALEXANDER R. TIGERMAN.
